UNITED STATES PATENT OFFICE.

ARCHIE OAKES, OF DETROIT, MICHIGAN, ASSIGNOR TO SQUARE D COMPANY, OF DETROIT, MICHIGAN, A CORPORATION OF MICHIGAN.

ELECTRICAL SWITCH AND METHOD OF PRODUCING SAME.

1,399,364.

Specification of Letters Patent.

Patented Dec. 6, 1921.

Application filed May 17, 1918. Serial No. 235,061.

To all whom it may concern:

Be it known that I, ARCHIE OAKES, a citizen of the United States, residing at Detroit, in the county of Wayne and State of Michigan, have invented certain new and useful Improvements in Electrical Switches and Methods of Producing the Same, of which the following, taken in connection with the accompanying drawings, forms a complete and exact description thereof.

My invention relates to electrical switches and the method by which such electrical switches may be produced. Switches of the type to which my invention relates are generally equipped with a plurality of movable contact blades and an operating cross-head of insulating material connected thereto, and it is the object of this invention to improve the manner of connecting such blades to the insulating cross-head.

One of the objects of this invention resides in an improved form of switch blade which materially reduces the cost of electric switch construction.

Another object of this invention resides in the production of an improved method of forming a connecting member upon the blade itself out of the material of which the blade is made.

A further object of this invention consists in the production of an improved method of switch blade construction which utilizes ordinary or standard strap copper or conducting metal from which the switch blades and connecting members are formed.

A further feature of this invention comprises the use of a cross-head of standard rectangular shaped insulating material of uniform cross section throughout.

One of the many possible forms that my invention may take is illustrated in the accompanying drawing in which—

Figure 1 represents the first stage in the operation of producing the blade member,

Fig. 2 represents the second stage in the operation,

Fig. 3 represents a third stage, and

Fig. 4 represents the final stage of the production of the switch blade, such blade being here shown ready for attachment to the connecting cross-head,

Fig. 5 shows the first operation of connecting the cross-head to the switch blade,

Fig. 6 shows the second operation of connecting the cross-head to the switch blade,

in which the connecting member is shown riveted in place,

Fig. 7 shows a plurality of switch blades connected to the cross-head whereby a multi-bladed switch may be formed,

60

Fig. 8 is a plan view of a portion of the cross-head showing the rectangular slot adapted to receive the rivet member.

This invention contemplates the using of standard commercial material to form both the cross-head and switch blades, thereby eliminating much of the expense in the production of electrical switches.

The first operation in producing this switch blade is shown in Fig. 1 in which two triangular openings or holes 1 are punched in the blade 2 in close relationship to each other with the outer or remote sides parallel and their bases in alinement and their apices adjacent the upper edge of the blade. 70

Figs. 2 and 3 show intermediate stages of drawing the material included between these two openings upwardly to form the rivet member, and it will be noted that as the sides of this rivet member approach parallelism 80 in the drawing process tangs 3 are formed by the upwardly turned corners or edges of the rivet member.

In Fig. 4 it will be seen that the sides of this rivet member have been drawn outwardly until they are parallel and that the rivet member projects above the upper edge of the blade and has two tangs 3 definitely formed thereon.

It will be seen from Figs. 1, 2, 3 and 4 90 that after the two openings 1 have been punched in the blade the metal therebetween is shaped into rivet form by the simple process of extrusion or the flowing of the metal upwardly by suitable means. At the same time that the sides are formed into parallelism it will be noted that the corners are bent upwardly and form tangs which readily lend themselves to riveting. The punching and drawing operation illustrated in 95 Figs. 1 to 4 can obviously be performed in a large variety of ways by those skilled in the art but are preferably performed in one operation by means of a compound punch and die.

100

From an inspection of Fig. 4 it will be seen that a clear space has been left for the seating of the cross-head 4. Upon the proper seating of such cross-head a washer 5 is slipped over the projecting portion of the 110

105

rivet member and the tangs 3 of such rivet member are then spread apart or riveted as shown at 6 in Fig. 6.

Attention is called to the fact that a forced fit is secured between the blade 2 and the cross-head 4 and may be secured between the rivet member and the opening 7 in such cross-head whereby upon the riveting of the rivet member a very rigid structure results.

10 The usual eyelet or connecting member 8 may be fastened to the cross-head intermediate 2 of the blades as shown in Fig. 7.

These blades are intended to form a portion of an electrical switch, but only so much 15 of the switch mechanism is illustrated as serves to clearly show my invention.

It will be seen that by the above means it is possible to use standard samples of metal 20 for forming the blades and standard insulating rectangular bar material for forming the cross-head and eliminate any additional screws or clamping members that have usually been used to secure the cross-head and blades together.

25 It will be seen that the blade may be formed in a very expeditious manner by suitable machines and in its finished form, as shown in Fig. 4, carries its own means of securing it to the cross-head.

30 The above description and the drawings are intended only as an illustration of one 35 of the modes in which applicant's invention may express itself and the invention is to be limited only as defined by the following claims:

1. An electrical switch comprising contact blades and a connecting cross-head therefor, said blades upon their upper side edges having a cutaway portion and an upwardly extending rivet portion projecting 40 from the bottom of the cutaway portion through the cross-head and beyond the upper edge of the blade members and riveted to said cross-head.

45 2. An electrical switch comprising contact blades and a connecting cross-head therefor, said blades having a rivet member formed integrally therefrom and projecting beyond the edge of the blades passing 50 through the cross-head and riveted thereto.

55 3. An electrical switch comprising contact blades and a connecting cross-head therefor, said blades upon their upper side edges having a cutaway portion and an upwardly extending rivet portion projecting from the bottom of the cutaway portion through the cross-head and beyond the upper edge of the blade members and riveted to said cross-head, the upper surface of the 60 cross-head and blades being flush.

65 4. An electrical switch blade having an upwardly extending rivet member formed integrally therefrom and projecting beyond the upper longitudinal edge of the blades.

5. The process of making an electrical

switch blade comprising punching two holes in said blade adjacent an edge thereof, outwardly drawing the material included between said holes to form a rivet member, alining the side edges of said rivet member, 70 and bending the corners thereof upwardly to form tangs adapted to be spread apart and riveted.

6. The process of making an electrical switch blade comprising punching two holes 75 in said blade adjacent an edge thereof, outwardly drawing the material included between such holes to form a rivet member projecting beyond the edge of the blade, alining the side edges of said rivet member 80 and bending the corners thereof upwardly to form tangs adapted to be spread apart and riveted.

7. The process of making an electrical switch having blades and an apertured cross-head, comprising punching a plurality of 85 holes in each blade, drawing the material included between said holes upwardly beyond the edge of the blade to form a rivet member, bending the corners of the rivet 90 members upwardly to form tangs, passing each rivet member through an aperture in the cross-head and riveting said rivet member to securely fasten said cross-head in place. 95

8. The process of making an electrical switch having a blade and an apertured cross-head, comprising punching a plurality of holes in the said blade, drawing the material included between said holes upwardly 100 beyond the edge of the blade to form a rivet member, passing such rivet member through the apertured cross-head and riveting said rivet member.

9. The process of making an electrical 105 switch having blades and an apertured cross-head, comprising punching a plurality of holes in each blade, drawing the material included between said holes upwardly beyond the edge of the blade to form rivet members, bending the corners of the rivet 110 members upwardly during such drawing process to form tangs, passing said rivet members through an aperture in the cross-head and riveting said rivet members by 115 spreading the tangs apart longitudinally of the blades to securely fasten said cross-head in place.

10. The process of making an electrical 120 switch having a blade and an apertured cross-head, comprising punching a plurality of holes in said blade, drawing the material included between said holes upwardly beyond the edge of the blade to form a rivet member, passing such rivet member through 125 the aperture in said cross-head and riveting said rivet member by spreading the upper corners thereof apart longitudinally of the blade.

11. The process of making an electrical 130

- switch having a blade, an apertured cross-head and a washer comprising punching a plurality of holes in said blade, drawing the material included between said holes upwardly to form a rivet member and passing said rivet member through the aperture in said cross-head and the washer positioned on the upper face of the cross-head and thereafter riveting said rivet member.
- 10 12. The process of making an electrical switch having a blade and an apertured cross-head, comprising punching two adjacent triangular holes having their bases in alignment, their remote sides parallel and their apices adjacent to the edge of the blade, drawing the material included between said holes upwardly until the edges thereof are parallel, thereby forming a rivet member and spaces to receive said cross-
- head, then passing said rivet member 20 through the aperture in said cross-head and seating said cross-head in said spaces and finally riveting said rivet member.
13. The process of making an electrical switch blade comprising punching two holes 25 in said blade adjacent an edge thereof and then extruding the material included therebetween to form a rivet member.
14. The process of making an electrical switch having a blade and a cross-head, 30 which comprises punching a plurality of holes in said blade, projecting the material included therebetween upwardly beyond the edge of the blade by extrusion of the material to form a rivet member, passing such rivet member through the cross-head and then riveting said rivet member.

35 ARCHIE OAKES.
